UNITED STATES PATENT OFFICE.

SAMUEL LIPPERT, OF CLEVELAND, OHIO.

THERMALLY-CONTROLLED FLOAT.

1,245,936.

Specification of Letters Patent.

Patented July 6, 1920.

Application filed June 29, 1918. Serial No. 106,574.

To all whom it may concern:

Be it known that I, SAMUEL LIPPERT, a citizen of the United States, and resident of Cleveland, in the county of Cuyahoga and State of Ohio, have invented certain new and useful Improvements in Thermally-Controlled Floats, of which I hereby declare the following to be a full, clear, and exact description, such as will enable others skilled in the art to which it appertains to make and use the same.

The objects of the invention are to provide an improved automatically acting valve having a thermally operated release outlet for air therein for draining the water of condensation and the oil from the pipes of a steam supply system, and adapted for use in a steam heating or power plant of any sort. The valve is designed to operate equally well at any elevation above or below the water level of the boiler, and will periodically release the liquid from the system without permitting the escape of the steam therefrom, and thus will provide dry steam, and prevent water hammer and make the action of the system quiet.

The invention embodies a gravity operating and self sealing steam trap which may be located on the vacuum line of a steam heating system, and has a chamber in which the water and oil collect and in which the liquid level can never rise beyond a predetermined point. The device can also be used to release the water and oil from steam pipes and chambers which are not on vacuum lines.

The invention includes a float operated valve located in a fluid collecting chamber spaced from the walls of the chamber and normally seated by gravity in such a manner as to exclude the passage of liquid or vapor, but which under the action of the accumulating liquid will rise and permit some of the liquid to pass, as soon as the liquid level has risen to the predetermined point or limit. The float will then immediately fall and prevent the passage of steam before all the liquid has been discharged from the chamber and thereby will always produce a timely seating of the valve to prevent escape of steam.

An important feature of the invention includes an air passage in the float permitting the air in the chamber to escape and the valve to rise, and an improved valve and a thermal element in said air passage

controlling said valve to prevent steam from escaping through the same.

The invention further comprises the combination and arrangement of parts and construction of details hereinafter described, shown in the accompanying drawings and specifically pointed out in the claims.

In the drawings,—

Figure 1 is a vertical section of the device.

Fig. 2 is a horizontal section thereof.

Fig. 3 is a vertical section of the thermally controlled float valve.

Fig. 4 is a side elevation of the float containing chamber connected to a steam distributing pipe which may be connected to a boiler.

In these views A is a cylindrical chamber or casing closed at its top and bottom and having vertical sides. B is an inlet opening at one side positioned above the lower end and having an upwardly rising or goose neck inlet passage b the lower edge b' of which forms a water seal between the inlet and the casing. At the bottom of the chamber is the outlet opening C provided with a valve seat C'. A float D in this chamber is provided with a valve E at its lower end which closes the outlet passage when it rests on the seat C'.

A cover F permits of access to the float and seat for cleaning or repairs if necessary.

The float is spaced from the vertical walls of the chamber by means of narrow flanges 90 or lugs G, serving as guides between which the water and oil readily pass, but which prevent the float from sticking to the walls.

Extending vertically and centrally through the float is a copper tube H forming an air 95 passage through which the air can descend to permit the float to rise in the chamber, since without this passage the compressed air in the chamber would prevent the float from rising.

A plug H' in the lower end of this tube supports a steel valve stem I, standing in the tube and having a valve I' at its upper end which closes against a seat at the top of the tube. Small holes K above the plug at 105 the lower end of the tube H permit the passage of air from the tube to the discharge pipe C.

The tube H is expanded when the steam comes in contact with it, and the lower end of the tube is slidingly movable in the lower end of the valve E as the tube expands, and

pulls down the attached valve stem I until the valve I' is closed, thus preventing the passage of steam therethrough.

The device can be attached to any steam pipe P in any convenient position as shown in Fig. 4.

In operation, the goose neck inlet B forms a water sealed passage to the float chamber, and as the water rises it flows over the wall 10 b' into the casing, the air in the casing escaping through the tube H and its valve I'. When the point of flotation of the float is reached the valve E opens and the water escapes through the outlet C. This action 15 siphons sufficient water from the inlet B into the casing and it immediately seals the valve E against steam escape. Steam then entering the casing expands the tube H and closes the valve I', and as the steam condenses the water forms a new seal in the 20 inlet passage and flows over the wall b' into the casing until the operation is repeated, the tube H meanwhile contracting and opening the air valve I' to prevent compression 25 of air in the float chamber.

I claim:

1. A device for the purpose set forth, comprising a float valve, an expansion tube extending therethrough and secured at the 30 upper end to said float, the lower end of said tube being slidable in the wall of said float, and an air valve in said tube control-

ling the passage of air through said tube, and connected to the lower end of said tube, whereby when said tube expands and contracts said valve is alternately closed and opened. 35

2. In a combined steam trap and liquid discharging device, a closed chamber provided with an outlet opening and valve seat 40 at its lower end and also provided with an inlet opening above the outlet opening, a float valve within said chamber coöperating with said seat, said float valve having a vertical thermally operated air outlet tube 45 carried thereby and extending therethrough, and a valve in said tube controlling the outlet therefrom.

3. In a combined steam trap and liquid discharging device, a chamber having a 50 water trap, a float therein, a thermal tube secured at one end in the wall of said float, and slidingly movable in the opposite wall forming an air escape passage, and a valve having a stem secured to the movable end 55 of said tube and adapted to move said valve to close said passage when said tube is expanded.

In testimony whereof I hereunto set my hand this 8th day of June, 1916.

SAMUEL LIPPERT.

In presence of—

J. P. VANA,
FRANK H. EWING.
